UNITED STATES PATENT OFFICE.

HOSEA W. LIBBEY, OF BOSTON, MASSACHUSETTS.

BICYCLE-FRAME.

SPECIFICATION forming part of Letters Patent No. 634,089, dated October 3, 1899.

Application filed October 1, 1898. Serial No. 692,457. (No model.)

To all whom it may concern:

Be it known that I, HOSEA W. LIBBEY, a citizen of the United States, and a resident of Boston, in the county of Suffolk and State of Massachusetts, have invented certain new and useful Improvements in Bicycle-Frames, of which the following is a specification.

The object of my invention is to produce a bicycle-frame that can readily and easily be put together or taken apart and which will be light and durable; and the invention consists of connecting-pieces, each having a diaphragm near its ends, a screw-threaded hole in said diaphragms, rods having at their ends right and left hand screw-threads to fit the screw-threaded holes in the diaphragms, the central portion of said rods having a boss by means of which they can be turned to connect or disconnect them, spacing-tubes of wood, papier-mâché, or other suitable material of the required length being placed upon the rods, as hereinafter set forth, and pointed out in the claim.

Referring to the accompanying drawings, Figure 1 represents a bicycle-frame embodying my invention. Fig. 2 is a section through one of the bars and connecting-pieces. Fig. 3 is a section of one of the T connecting-pieces having diaphragms. Fig. 4 is a view of one of the rods, and Fig. 5 is a section of one of the spacing-tubes.

A represents the connecting-pieces, having a diaphragm *a* at each end where it is desired to connect a bar. These diaphragms are each formed with a screw-threaded hole, one thread being right-handed and the opposite one left-handed.

B is a rod or bar having a right-hand screw-

thread at one end and a left-hand screw-thread at the other. On the central portion 40 of each rod a boss *b* is secured by shrinking or any other convenient manner. The outer surface of this boss may be of any desired form to receive a spanner, so as to turn the rod, but I prefer to form it round and have a 45 hole or holes in its perimeter, as shown, so that it can be turned by a tool adapted to fit same.

On each end of the rod *B* is fitted a spacing-tube *C*, of wood, papier-mâché, or other suitable material, that has been cut to a length to fit the required distance between the diaphragm *a* and the boss *b*, so that when the rod *B* is screwed up tight the ends of said tube will abut against the diaphragm *a* and the boss *b*, thus holding all the parts together. It will be seen that by this construction a very light, strong, and rigid frame is produced and one which will be more ornamental than the ordinary painted frame, as any kind 60 of wood desired can be employed for the tubing and a much lighter frame will be produced.

What I claim is—

In a tubular bicycle - frame, connecting-pieces formed with diaphragms having screw-threaded holes, rods having screw-threaded ends and a central boss whereby same may be turned and spacing-tubes of suitable material substantially as set forth.

In testimony whereof I have affixed my signature in presence of two witnesses.

HOSEA W. LIBBEY.
